MORRIS M. BESKIND AND JACK MAYPER, OF BROOKLYN, NEW YORK, ASSIGNEES TO
WASHINGTON GARTER CORP., OF NEW YORK, N. Y., A CORPORATION OF NEW YORK

STITCHLESS GARTER CLASP

Application filed April 6, 1932. Serial No. 603,568.

Our invention relates to improvements in hosiery engaging clasps for garters and it is our object to produce a clasp for engaging the hosiery in which the various parts are held together without sewing or stitching. It is well known that where the web at the clasp is sewed or stitched the fabric of the web is weakened and the garter is easily torn at the line of stitching and rendered 10 useless. By the use of our invention this difficulty is entirely eliminated.

In the drawing Fig. 1 is a face view of our improved garter clasp structure; Fig. 2 a longitudinal, sectional view of the structure 15 of Fig. 1; Fig. 3 a view of the slide used in our garter; Fig. 4 a view of the loop used in our garter; Fig. 5 a view of a button plate used in one form of our garter; Fig. 6 a view of the tipped web used in our garter; Fig. 7 20 a view of a slide and loop mechanically hinged together which may be used in our garter; Fig. 8 a face view of a garter clasp embodying a modified form of button plate; and Fig. 9 a longitudinal, sectional view of 25 the structure of Fig. 8.

The web 1 has the rigid tip 2 secured to one end thereof.

The slide 3 has the slots 4 and 5 and the bar 6 between them.

30 The loop 7 has the top bar 8.

The button plate 9 shown in Fig. 5 has the slots 10 and 11 and the button 12 mounted thereon.

The button plate 9' shown in Figs. 8 and 9 35 has the slot 10' at one end and the button 12' at the other end.

In assembling the garter clasp shown in Figs. 1 and 2 the tipped end 2 of the web 1 is threaded through the slot 4 in the slide 3 40 from rear to front, then the bar 8 of the loop 7 is slipped on the web; the web then passes through the slot 5 in the slide 3 from front to rear. It then drops to form a loop and is threaded through the slot 10 in the button 45 plate 9 from front to rear, then through the slot 11 in the button plate from rear to front and carried around the button plate 9 and up and again through the slot 4 in the slide 3 from rear to front after which the 50 tipped end 2 is threaded through the slot 5

in the slide 3 from front to rear. In this way the loop 7 is held to the slide 3 by the web 1 and the tipped end 2 of the web is held in position between the reaches 13 and 14 of the web 1 so that it cannot be accidentally withdrawn. In this way we are enabled to assemble the garter clasp without the use of any stitching and avoid the weaknesses incident to the use of sewing. 55

In assembling the modification shown in Figs. 8 and 9 the tipped end 2 of the web 1 is passed from front to rear through the slot 4 in the slide 3, then through the slot 5 in the slide 3 from front to rear; the top bar 8 of the loop 7 is then strung on the web; the web is then passed through the slot 10' in the button plate 9' from front to rear; then again through the slot 4 in the slide 3 from rear to front and finally again through the slot 5 in the slide 3 from front to rear, leaving the 70 tipped end 2 lying in the folds of web. 80

It will be noted that so far as the threading of the web on the slide 3 is concerned the method is the same in both forms of our invention, and that the button plate 9 or 9' is 75 secured to the clasp by a long loop of web in the case of the button plate 9 or a short loop in the case of the button plate 9'. 75

If desired the loop 7' may be mechanically hinged to the slide 3' as shown in Fig. 7 without departing from our invention and the structure of Fig. 7 threaded in the manner herein described so that no stitching is required to hold the parts together. 80

In use the hosiery is placed over the button 85 and the loop slipped thereover in the usual manner.

We claim:—

1. In a stitchless garter clasp the combination of a slide provided with two slots, a button plate provided with a slot, a button thereon, a loop adapted to engage said button and a web, a tip on said web, said web passing through one slot in said slide, then 90 through the second slot in said slide, downwardly and through the slot in the button plate, then up and again through a slot in the slide and then through the second slot in said slide with the tipped end lying between 95 100

reaches of web, and means for swingingly securing the loop to the slide.

2. In a stitchless garter clasp the combination of a slide provided with two slots, a button plate provided with a slot, a button thereon, a loop adapted to engage said button, a web and a tip on the end of said web, said web passing through one of the slide slots from rear to front, then through the other slide slot from front to rear, thence through said loop and slot in the button plate from front to rear, thence up to and again through one of said slide slots from rear to front and finally again through the other of said slide slots from front to rear whereby the tipped end of the web lies between reaches of web.

3. In a stitchless garter clasp the combination of a slide provided with two slots, a button plate provided with two slots, a button thereon, a loop adapted to engage said button, a web and a tip on the end of said web, said web passing through one slot in the slide, over the loop, through the second slot in said slide, through one slot in the button plate, through the other slot therein, around the end of the button plate and up to and through a slot in the slide, thence through the other slot in the slide with the tipped end lying between reaches of web.

4. In a stitchless garter clasp, a slide provided with two slots, a loop hingedly secured thereto, a button plate provided with two slots, a button thereon, a web and a rigid tip on the end of the web, said web being threaded through one of the slide slots from rear to front and through the other slide slot from front to rear, thence through one of said button plate slots from rear to front and through the other of said button plate slots from rear to front, thence around the bottom edge of the button plate and up to and again through a slot in the slide from rear to front, thence through the other slide slot from front to rear whereby the tipped end of the web lies between reaches of the web.

In testimony whereof, we have affixed our signatures.

80
